FILING MACHINE

Max Goldberg, New York, N. Y.

Application June 6, 1934; Serial No. 729,309.

12 Claims. (Cl. 226—46)

This invention relates to a filling machine which may be used advantageously for filling mattresses and pads with padding, inner springs, etc.

The principal object of the invention is the provision of a machine of the indicated character embodying improvements whereby the machine will be compact, efficient in construction and operation, and of comparatively increased filling capacity.

Another object of the invention is to provide a filling machine of the type designed to insert the filling material in the mattress cover or tick by means of a roller and pronged plates which force the filling material through a filling spout into a cover or covers arranged on said spout.

Another object of this invention is to provide supplementary reciprocable link members which complete pushing the aforesaid pronged plates and filling material through the filling spout and are then automatically withdrawn to their original inactive position after the filling operation.

Another object of this invention is to provide a filling machine having an operating table, means for carrying the filling material to the filling spout, and having sprocket chains and supplementary link members pivotally mounted on said chains for pushing the filling material through the spout, the said link members being adapted to swing away from said chains into inactive position.

Another object of this invention is to provide horizontal sprocket chains having end portions mounted in angular relation, the said link members being adapted to follow the said angular chain portions so as to make the filling machine more compact.

Another object of this invention is to provide a universal filling machine adapted to fill one mattress cover, or two mattress covers simultaneously, or for filling a hinged mattress cover.

With the above and other objects in view the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which

Figure 1 is a longitudinal sectional view of the filling machine, the section being taken as on line 1—1 in Figure 2.

Figure 2 is a plan view of the filling machine.

Figure 3 is a vertical sectional view, the section being taken as on line 3—3 in Figure 2.

Figure 4 is an end view of the machine, the lower portion being broken away, and showing two small spouts.

Figure 5 is an enlarged side view showing mechanism for actuating the roller.

Figure 6 is a side view of the roller actuating mechanism.

Figure 7 is an end view of the machine, the lower portion being broken away, and showing a single spout of maximum width.

Figure 8 is an end view showing rack and gear mechanism which may be used for actuating the slideable end members of the spout.

In the illustrated embodiment of the invention, the several views show a filling machine 10, comprising a table 11 of suitable width to accommodate the largest size mattress. The table 11 is mounted on a front frame 12 and a rear frame 20 13. Upright side members 14 are mounted on the table 11 and are hinged by pivot pins 15 to end wall extensions 16 of movable spout members 17. The side members 14 are supported at their free rear ends from the upper surface 18 of the rear frame 13 by means of angularly bent rods 19. The side members 14 and the movable spout members 17 are thus jointly adjustable over the table 11 according to the width of the mattress cover or the like to be filled.

As best shown in Fig. 4, the vertical end walls 20 of the movable spout members 17 are integral and in right angular relation with lower horizontal walls 21. The horizontal walls 21 are provided at their rear ends with downwardly extending flanges 22. The lower ends of the flanges 22 are bent to provide upwardly extending portions 23 which engage with the lower edge of a cross-bar 24. The cross-bar 24 is fixed to the uprights 25, 25' of the frame 12. The cross-bar 24 serves to maintain the lower spout members 17 in slideable horizontal position. Right angular upper movable spout members 26 similar to the lower movable spout members 17, are positioned above the spout members 17 and are provided at 45 their rear ends with upwardly extending flanges 27. The upper ends of the flanges 27 are bent to provide downwardly extending portions 28 which engage the upper edge of an angle iron 29. The spout members 26 comprise vertical end walls 31 which are integral and in right angular relation with respect to the upper horizontal walls 32. The angle iron 29 extends transversely of the machine and its opposite ends are fastened respectively to end plates 30. The angle iron 29 55

serves to maintain the upper spout members 26 in slidable horizontal position.

The movable spout members 17 and 26 are respectively in telescoping relation with lower horizontal plates 33 fixed to the cross-bar 24 and upper horizontal plates 34 fixed to the angle iron 29. One of the fixed plates 34 is provided with a hinged flap 35 which may be swung down as shown in Figure 4, to complete the formation of a rectangular spout 36. Similarly, one of the fixed plates 33 is provided with a hinged flap 37 which may be swung up to complete the formation of a rectangular spout 36'. As shown in Figure 7, the flaps 35 and 37 may be swung into horizontal position and form a single rectangular spout 38 which may extend substantially the full width of the table 11. It will be understood that means is employed to provide the machine with a single filling spout for filling relatively large mattress covers, ticks or the like, and also to provide a plurality of filling spouts for simultaneously filling a plurality of covers, etc.

As best shown in Figures 2 and 3, plates 39 are mounted in overlapping relation with plates 40 on the table 11, between the side members 14. The plates 39 and 40 are provided with pins 41 which are adapted to enter into apertures 42 in a cross-bar 43. The plates 39 and 40 and cross-bar 43 are slidably mounted upon the table 11. A plurality of spring prongs 44 are secured to the upper surfaces of the plates 39 and 40. The prongs 44 on the plates 39 and 40 extend upwardly and forwardly toward the front or spout end of the machine.

As best shown in Figure 1, angle members 45 and channel members 46 are fastened to the lower plates 40 and form receiving means for a pusher-bar 47 extending transversely of the table 11. The pusher-bar 47 is adapted to operate in conjunction with the wide spout 38 shown in Figure 7. The spout 38 is designed for filling mattress covers of a width corresponding to the maximum width of the table 11. The spout arrangement 36 and 36' shown in Figures 2 and 4 is designed for filling simultaneously two narrow mattress covers.

Sprocket chains 48 are mounted on sprocket gears 49 on shafts 50 at opposite ends of the machine. The shafts 50 extend transversely of the machine and are supported by the frames 12 and 13. The upper portions of the chains 48 slide on the table 11. The cross-bar 43 is fastened at both ends to the sprocket chains 48. As shown in Figures 5 and 6, a motor 51 has a pinion gear 52 on its shaft in mesh with a gear 53 which is fixed to one of the sprocket chain shafts 50. The motor thus connected serves to drive the sprocket chains 48, which in turn, by virtue of the cross-bar 43, move the pusher-bar 47, and the pronged plates 39 and 40, so as to cause a batch of filling material placed on the pronged plates to be carried into the narrow spouts 36 and 36' or to the wide spout 38.

Mounted in suitable bearings in the end plates 30 is a feed and compression roller 54 designed to bear upon and compress the filling material carried by the pronged plates 39 and 40, and also to push the filling material through the spout. As shown in Figure 1, the roller 54 is provided with prongs 55 projecting radially therefrom. The prongs 55 serve to grip and compress the filling material down to the height to which the spout has been set. The prongs 55 also augment the movement of the filling material through the spout. The roller 54 must be vertically adjustable in order to vary the space between the roller

and the bottom of the spout and thus control the thickness of the filling material so as to adapt the machine for making mattresses of different thicknesses. This vertical adjustment is effected by supporting the end plates 30 from a transverse shaft 56 by means of links 57 and 58 and by providing a worm gear 59 and a worm 60 for actuating the shaft 56. The shaft 56 is supported by the uprights 25 and 25' of the frame 12. The links 57 are fixed to the shaft 56 and are pivotally connected with the links 58 respectively, and the links 58 are pivotally connected with the plates 30 respectively. The gear 59 is secured to the shaft 56 and the worm 60 which meshes with the gear 59 is secured to a shaft 64. The uprights 25, 25' of the front frame 12 are provided with vertical, oblong slots 61 forming guides for oblong members 62 fastened to the end plates 30. Inasmuch as the upper spout members 26 and 34 are supported from the angle iron 29 which is fastened to the end plates 30, the said spout members as well as the roller 54 are supported from the shaft 56. The operator may, by rotating a hand wheel 63 on the shaft 64, raise or lower the roller 54 and the upper members of the spout 25 simultaneously.

The roller 54 is mounted on a shaft 65 supported by the members 62, and is driven from a sprocket pinion 66 on one of the transverse shafts 50, by means of a sprocket chain 67 and a sprocket pinion 68 mounted on a shaft 69. The shaft 69 is supported by bearings in parallel plates 70 mounted to swing on the shaft 65. A pinion gear 71 on the shaft 69 meshes with a gear 72 on the shaft 65. Motion is transmitted from the sprocket chains 48 to the roller shaft 65 through the intervention of the pinions 66 and 68, chain 67 and gears 71 and 72. A supporting link 73 having bearings for the shafts 50 and 69 serves in cooperation with the plates 70 to constrain the pinion gear 71 to remain in mesh with the gear 72 in any of the vertical positions that the gear 72 is adjusted by rotation of the hand wheel 63. It will thus be noted that the roller 54 is at all times driven in unison with the sprocket chains 48 and the pronged plates 39 and 40.

As shown in Figure 1, the sprocket chains 48 have end portions 74 extended vertically. Link members 75 are mounted on pivots 76 on the sprocket chains 48 and are respectively provided with hooks 77 at the free ends. Each link member 75 is provided with a counterweight 78 beyond the pivot 76. The link members 75 are constrained to follow the movements of the sprocket chains from a vertical inactive position to a horizontal operative position. It will thus be noted that when the sprocket wheels 49 are rotated a portion of the circumference, so as to cause the vertical end portions 74 of the sprocket chain 48 to ride, the link member 75 will rise and swing down into engagement with the channels 46 and will move horizontally with the pusher-bar 47. It will be observed that as the pusher-bar 47 passes beyond the roller 54, the pronged plates 39 and 40 will rest upon the lower inner surfaces of the spout. The pins 41 of the cross-bar 43 becomes disengaged from the apertures 42 in the pronged plates 39 and 40, and the cross-bar 43 being connected to the chains 48 follows the chains in their movement under the operating table 11. The link members 75 being in engagement with the channels 46 will now push the pronged plates 39 and 40 through the spout. On reversing the motion of the sprocket chains, the pronged plates will be pulled out from the spout 75.

and the pins 41 in the cross-bar 43 will become reengaged with the apertures 42 in the pronged plates 39 and 40, this reengagement taking place at the same point where they became disengaged.

5 The plates 39 and 40 are moved rearwardly both by the pins 41 and the link members 75, and on reaching the rear frame 13, where the end portions of the chains have been extended in right angular relation, the link members 75 will follow 10 the movements of the said angular chain portions, as shown in dot and dash lines, and assume a vertical position. The vertical end portions 14 function to reduce the length of the operating table 11 and of the filling machine 10. It is to 15 be noted that the angular chain portions 14 serve to lower the link members 75 below the operating table 11. The said portions 14 may however be dispensed with and the link members 75 will then assume a vertical upright position above the 20 table when reaching the rear frame 13.

As shown in Figures 2 and 3, two longitudinal plates 79 are hinged respectively to the plates 40 by hinges 80. When the plates or flaps 79 are set in right angular relation with the plates 40 25 and the flaps 35 and 37 of the spouts 36 and 36' are set in right angular relation with the fixed horizontal plates 33, as shown in Figure 4, the filling machine 10 becomes adapted for inserting two independent mattress fillings into separate mattress covers simultaneously. When the flaps 79 are swung down into horizontal position and the spout flaps 35 and 37 are swung horizontally to the position shown in Figures 7 and 8, the filling machine 10 becomes adapted for filling one wide 35 mattress cover extending the entire distance between the upright side members 14.

As shown in Figure 8, rack and gear mechanism may be used to close up the slidable end members of the spout and to compress the filling material contained therein so as to permit the mattress cover to be easily placed over the spout. A plate 81 is suitably fastened to the uprights 25, 25' of the front frame 12 and is provided with rack teeth 82 adjacent the slidable end members 20 of the spout. Gear segments 83 are rotatably mounted in movable members 84 which are fastened at their lower ends to the end members 20 of the spout. Levers 85 are fixed to the gear segments 83. It is thus possible by actuating 40 the levers 85 to forcibly close up the slidable end members 20 of the spout. It is to be noted that the gear segments 83 in the position shown in Figure 8, are not in engagement with the rack teeth 82 and permit movement of the movable 45 end members of the spouts and the attached gear segments 83 over the fixed rack teeth 82. This enables the adjustment of the spout members by hand before swinging the levers 85 into engagement with the rack teeth 82 for forcibly 50 bringing the end members closer together so as to permit the mattress cover to be more easily slipped over the spout.

The operation of the mattress filling machine is as follows:

55 The spout members 17 and side members 14 are set to the width of the mattress to be filled. The filling material is placed on the pronged plates 39 and 40 and the carrying and pushing mechanism and the roller 54 are operated to force the filling material through the spout into the cover arranged thereon to fill the cover. The lever 85 is swung to bring the slidable end members of the spout closer together thus compressing the filling material in the spout and reducing the 60 width of the spout so as to permit the mattress 70

cover to be more easily slipped over the spout. The lever 85 is then swung back causing the filling material in the spout to spread apart sideways and cause the cover to be held in frictional engagement over the spout.

5 The drive mechanism then causes the roller 54 to compress and feed the filling material into the spout in unison with the movement of the pronged plates; and the supplementary link members 75 push the material through the spout 10 until the mattress cover is entirely filled. It is obvious that any suitable reversing means may be employed for reversing the motor, to reversely actuate the filling mechanism.

When filling wide mattress covers, the wide 15 pusher-bar 47 is used in the spout 38. When filling two narrow mattress covers simultaneously or a longitudinally hinged mattress cover, the pusher-bars 47' are used in the narrow spouts 36 and 36'.

20 It will be seen that by the use of the machine herein described, mattresses of any thickness from three to eight inches can be filled by adjusting the vertical elevation of the roller 54 to the thickness of the mattress wanted, and that 25 the walls of the spout are automatically adjustable vertically and manually adjustable horizontally to the thickness and width of the mattress to be made.

I claim:—

30 1. A filling machine of the class described, comprising a table, a plurality of flat plates mounted to slide longitudinally on said table, said plates being in overlapping relation and laterally adjustable, two side walls adjustable laterally with respect to said table and plates, a vertically adjustable roller at the discharge end of said machine, a spout located at said discharge end and being made of a plurality of laterally and vertically adjustable members, two spaced 40 and adjacent longitudinal plates hinged respectively to certain of said slide plates and adapting said machine to insert two independent mattress fillings into separate mattress covers simultaneously when said hinged plates are in 45 right angular relation with said flat plates.

2. A filling machine of the class described, comprising a supporting member, a plurality of carrier members mounted to slide longitudinally on said supporting member, two side walls adjustable laterally with respect to said supporting member and carrier members, a vertically adjustable roller at the discharge end of said machine, a spout located at said discharge end and being made of a plurality of adjustable 50 members, two spaced and adjacent longitudinal plates hinged respectively to two adjacent carrier members and adapting said machine to insert two independent mattress fillings into separate mattress covers simultaneously when said 55 hinged plates are in right angular relation with said supporting member.

3. In a filling machine of the class described, an adjustable spout comprising fixed central members and slidable end members, said end 65 members being telescopically mounted over said central members, said central members having hinged flaps adapted for right angular adjustment thereto for subdividing said spout into two smaller spouts.

70 4. In a filling machine of the class described, an operating table, a spout at the discharge end of said machine, means for delivering filling material along said table to said spout, said means comprising sprocket chains having horizontal 75

- portions and end portions mounted in angular relation thereto and having supplementary link members pivotally mounted thereon, said link members being adapted to swing away from said horizontal portions of the chains and follow the said angular chain portions.
5. In a filling machine, filling material carrier members, means for supporting said carrier members, said carrier members being reciprocable on said support, a spout at the discharge end of said machine, means for reciprocating said carrier members with respect to said spout, said reciprocating means including chains in angular relation with respect to said support; and means 10 on said chains which coacts with means on said carrier members contributing in reciprocating said carrier members at certain intervals.
6. In a filling machine, filling material actuating means reciprocably mounted on a support, 20 a spout at the discharge end of said machine, means for reciprocating said actuating means with respect to said spout, a portion of said actuating means being positioned in an angular direction at the opposite end of the machine, 25 and additional means co-operating with said first and second means contributing in reciprocating said first means at certain intervals.
7. In a filling machine of the class described 30 an operating table, a spout at the discharge end of said machine, mechanism for carrying filling material along said table, said mechanism comprising horizontal sprocket chains movable on said table, a material pusher connected with said chains, link members arranged in spaced relation, said link members being pivotally secured 35 at their forward ends to said chains respectively, and having means for engaging said pusher at their free ends for moving said pusher through said spout, said link members being adapted to 40 swing away from said chains into angular relation thereto.
8. In a filling machine of the class described, 45 fixed, slidable and hinged spout forming sections, said slidable sections being adjustable with respect to the fixed sections to vary the width of the spout, and said hinged sections being movable to positions to form two separate spouts.
9. In a filling machine of the class described, 50 in combination, driving elements, a filling spout arranged beyond said elements, a carrier on which material may be placed to be carried thereby through said spout, coacting means on said elements and carrier to cause the latter to move with the former a predetermined distance with 55 respect to said spout, and additional means connected with said elements and carrier to move

the latter beyond said predetermined distance with respect to said spout.

10. In a filling machine of the class described, 5 a spout adapted to receive an article to be filled with desired material, a material carrier movable forwardly and rearwardly with respect to said spout, the forward end of said carrier being withdrawn from said spout when the carrier is in its rearward position, driving means, engaging and releasing means to cause the carrier to be moved 10 forwardly a predetermined distance by said driving means and then release the carrier, and additional means cooperating with the carrier and driving means to cause the carrier to be moved forwardly further by continued operation of the 15 driving means after the release of the second means, and to cause rearward movement of the carrier upon the reverse operation of the driving means, said second means becoming engaged during the rearward movement of the carrier to complete the rearward movement thereof to its rearward position.

11. In a filling machine of the class described, 20 a spout adapted to receive an article to be filled with desired material, a material carrier movable forwardly and rearwardly with respect to said spout, the forward end of said carrier being withdrawn from said spout when the carrier is in its rearward position, driving means including 25 endless chains, engaging and releasing means to cause the carrier to be moved forwardly a predetermined distance by said chains and then release the carrier, and additional means cooperating with the carrier and chains to cause the carrier to be moved forwardly further by continued 30 operation of the driving means after the release of the second means, and to cause rearward movement of the carrier upon the reverse operation of the driving means, said second means becoming engaged during the rearward movement 35 of the carrier to complete the rearward movement thereof to its rearward position.

12. In a filling machine of the class described, 40 spout forming sections consisting of fixed intermediate plate sections arranged in spaced relation one above the other, adjustable hollow sections disposed in telescopic relation to said plate sections, and hinged plate sections, the provision 45 and arrangement being such that the adjustable and hinged sections may be disposed relatively to the fixed sections to optionally form two separate spouts, or a single spout, and the size of the two spouts and the single spout being varied by adjustment of said adjustable sections.

55

MAX GOLDBERG.
